UNITED STATES PATENT OFFICE

CHARLES C. NUSS, OF WASHINGTON, PENNSYLVANIA

AUTOMOBILE HEATING SYSTEM

Application filed May 31, 1929. Serial No. 367,488.

In the past it has been a matter of common knowledge that the water of the cooling jacket of an internal combustion engine may be circulated through heat radiators to warm the interior of an automobile. Likewise, by employing suitable means, heat may be abstracted from the exhaust passage of the engine to heat the car. The present invention involves certain improvements in car-heating systems by means of which the heat derived from these known sources is utilized in a particularly effective manner.

In the accompanying drawing Fig. I is a view, partially in side elevation and partially in section, of the fore portion of a motor car, and illustrates the heating system of the present invention; and Fig. II is a schematic view in side elevation of an automobile motor, showing the heating system with a certain modification adapted thereto.

Referring to the drawing, the car motor 2 has an upper connection 3 to the cooling radiator 4. This upper connection, and a lower communication which is not shown in Fig. I, permits circulation of water through the cooling jacket 20 of the motor and the radiator 4. In the exhaust passage 5 leading from the motor is an auxiliary heater 6, which is effective to impart heat from the exhaust gases of the motor to the water circulating within the heating system.

A conduit 7 is tapped into the water jacket 20 of the motor, and carries hot water downward therefrom to the auxiliary heater 6 wherein it becomes more highly heated before passing upward through pipe 8 to the car heating radiator 9. The conduit 7 communicates with the circulating cooling water adjacent the bottom of the water jacket 20, as indicated in the drawing. Moving in the direction of the arrows, the water flows through the pipe 10, and back to the jacket water in connection 3 the uniting of pipes 3 and 10 being at a point of higher elevation than said heat radiator 9. Water being drawn from the cooling jacket 20 through connection 3 to the radiator 4, will obviously aspirate water from the pipe 10 at the point 11. This aspirating action aids the natural gravity and buoyancy forces in causing the water to move

through the system as described. Cocks 12 may be inserted in the piping at suitable points to serve as means for closing and emptying the pipes when car heating is not desired.

It is important that the water be superheated before it enters the radiator 9 to insure a high degree of water heat within the radiator. Only part of the jacket water is utilized; that is to say, only a fractional portion of the circulating jacket water flows through the heating system. As a result, the water in the heating system flows at a moderate rate, and permits the heater 6 to raise the water to a high temperature before it enters the radiator 9.

Fig. II shows a modification, which comprises a pipe 13 interconnecting the circulating pump 14 and the radiator inlet pipe 8. The three way cock valve 15 normally allows the fluid flow to occur as above described. This valve may, however, be operated to bypass all, or a portion, of the water from the heater 6 directly to the pump and water jacket circuit. Thus, by means of a single valve, the amount of hot water admitted to the radiator 9 may be minutely regulated.

I claim as my invention:

A heating system in combination with an automobile having a motor, a water jacket for the motor, a radiator for cooling the water of said jacket, an outlet conduit from the water jacket to the top of said cooling radiator, and an exhaust passage for the hot products of combustion of said motor; which heating system comprises a water heater associated with said exhaust passage, a heat radiator connected to said water heater, a pipe connecting said heat radiator with the outlet conduit of said water jacket at a point of higher elevation than said heat radiator, said pipe being so disposed relatively to said outlet conduit that an aspirating effect is had upon the water in such pipe, and a heater-feeding pipe leading downward from a point adjacent the bottom of said water jacket to said water heater, the water of said jacket, at the point where its withdrawal is effected by said feeding pipe, being at a lower temperature than the water in said outlet conduit,

whereby the temperature gradient of the water in the heating system, together with the relative location of the water heater, the heat radiator and the conduits, combine in creating maximum buoyancy forces to co-operate with the said aspirating effect for producing the flow of water through the heating system.

In testimony whereof I have hereunto set my hand.

CHARLES C. NUSS.
